DESIGN FOR A BOOK END

John Ferdinand Oberwinder, St. Louis, Mo.,
assignor to Glenmore Distilleries Company,
Louisville, Ky., a corporation of Delaware

Application March 4, 1947, Serial No. 137,335

Term of patent 3½ years

(Cl. D33—1)

To all whom it may concern:

Be it known that I, John Ferdinand Oberwinder, a citizen of the United States, residing at St. Louis, an independent city, and State of Missouri, have invented a new, original, and ornamental Design for Book End, of which the following is a specification, reference being had to the accompanying drawing, forming part thereof.

In the drawings:

Figure 1 is a perspective view of my new and ornamental book end seen from the end, and

Figure 2 is a perspective view of my new and ornamental design looking from the front.

I claim:

The ornamental design for a book end, as shown.

JOHN FERDINAND OBERWINDER.
